UNITED STATES PATENT OFFICE

128,221

DESIGN FOR AN ENVELOPE

William Whiting, Holyoke, Mass.

Application April 26, 1941, Serial No. 100,635

Term of patent 3½ years

To all whom it may concern:

Be it known that I, William Whiting, a citizen of the United States, residing at Holyoke, in the county of Hampden and State of Massachusetts, have invented a new, original, and ornamental Design for Envelopes, of which the following is a specification, reference being had to the accompanying drawing, forming part thereof.

Figure 1 is a view of the back of an envelope embodying my new design with the flap shown open, and

Figure 2 is a plan view of the envelope shown in Figure 1 in unfolded condition.

The face or front of the envelope is conventionally plain.

I claim:

The ornamental design for an envelope, substantially as shown and described.

WILLIAM WHITING.
